PIANO FLANGE REAMER AND REPINNING
TOOL

Charles B. Archer, Homestead Park, Pa.

Application November 12, 1952, Serial No. 319,886

6 Claims. (Cl. 81—5.1)

1

This invention relates to tools used primarily for repairing piano actions, and in particular a tool having pivotally connected handles between which a piano flange is clamped with a reamer slidably mounted in one handle and actuated by a hand lever pivotally mounted on the handle for forcing a pin through one side of the flange and for reaming the opening for the pin in the flange by spinning the reamer, and a plunger slidably mounted in the other handle, aligned with the reamer and adapted to be actuated by a hand lever pivotally mounted on the other handle for returning the pin to its position in the flange.

The purpose of this invention is to eliminate guess work and at the same time expedite repairing flanges of piano actions.

The conventional manner of repairing a piano action or doing a releasing job of the action is to remove the pin pivotally mounting a hammer butt or jack in the flange by driving the pin out with a special punch, withdrawing it with special pliers and then reaming out the opening with a tapered reamer which removes a little of the material of the bushing. Removing $\frac{1}{1000}$ of an inch too much of the bushing may make it necessary to replace the bushing and pin and if too little is removed it may be necessary to repeat the operation. In numerous instances it is necessary to use new pins and in fitting the pins the bushings are accidentally pushed out of the openings in the flanges. With these thoughts in mind this invention contemplates one complete tool in which piano action flanges are positioned whereby a reamer drives the pin from one side of the flange so that the opening may be reamed out with the reamer and wherein after returning the pin with the same tool the position of the flange is reversed and the same action or operation repeated in the other side.

The object of this invention is, therefore, to provide a piano action repair tool that reams out bearing bushings in the sides of a piano action flange and returns the pins to the reamed openings.

Another object of the invention is to provide a piano action repair tool whereby openings for pins connecting hammer butts and jacks to flanges are reamed out without completely removing pins pivotally connecting the hammer butts and jacks to the flanges.

A further object of the invention is to provide a piano flange repair tool which is of a simple and economical construction.

With these and other objects and advantages

in view the invention embodies a tool having upper and lower handles pivotally connected at one end with a reamer slidably mounted in the upper handle and actuated by a hand lever pivotally connected to the handle and in which a plunger, slidably mounted in the lower handle and aligned with the reamer is actuated by a lever pivotally mounted on said lower handle.

Other features and advantages of the invention will appear from the following description taken in connection with the drawings, wherein:

Figure 1 is a side elevational view illustrating the improved piano action repair tool.

Figure 2 is a plan view of the tool showing a hammer butt extended from one side of the tool.

Figure 3 is a vertical cross section through the tool taken on line 3—3 of Fig. 1 showing a reamer positioned to force a pin from a flange in the tool and a plunger for returning the pin.

Figure 4 is a detail taken on line 4—4 of Fig. 1 looking upwardly toward the under surface of the upper handle and showing a flange holding guide pivotally mounted on the under surface of the upper handle.

Figure 5 is a vertical section similar to that shown in Fig. 3 with the parts shown on an enlarged scale and showing the reamer extended through one side of the flange of the piano action.

Figure 6 is a detail similar to that shown in Figs. 3 and 5 showing the pin returned to its position in the flange.

Figure 7 is a section showing the piano action flange reversed with the reamer positioned to release the pin in the opposite side of the flange.

Figure 8 is a detail showing a piano action hammer and flange looking toward the under surface of the upper handle of the tool.

Figure 9 is a vertical section also similar to that shown in Figs. 3 and 5 illustrating the device used in removing the pin whereby the plunger is omitted from the lower handle.

Figure 10 is a vertical section similar to that shown in Fig. 9 showing a new pin inserted in the flange.

Figure 11 is a view similar to that shown in Fig. 10 showing the position of the pin holder reversed whereby the new pin is extended through the flange, and the old pin removed.

Figure 12 is a detail showing a plurality of reamers of different sizes.

Figure 13 is an end view of one of the reamers.

Figure 14 is a view showing a plurality of pins of different sizes.

Figure 15 is a detail showing a pin holder with part of the holder broken away and shown in section.

Figure 16 is a detail illustrating the plunger for returning the pins to operative positions in the flanges.

Referring now to the drawings wherein like reference characters denote corresponding parts the improved piano action repair tool of this invention includes an upper handle 10, a lower handle 11, a reamer 12 having a shank 13 with a head 14, a reamer actuating lever 15 pivotally mounted on the upper handle 10, and a plunger 16 slidably mounted in an opening 17 in the lower handle 11 and positioned to be actuated by a hand lever 18 15 pivotally mounted on the lower handle.

The handles 10 and 11 which are pivotally connected by a pin 19 are formed with enlarged sections 20 and 21, respectively, and the hand levers 15 and 18 are pivotally mounted on the enlarged 20 section with pins 22 and 23.

The lever 15 is provided with a cam 24 that is positioned to engage the end surface of the head 14 on the shank 13. The head 14 is secured to the shank with a set screw 25 and the shank is 25 slidably mounted in a bore or opening 26 in the enlarged section 20 of the handle 10.

The plunger 16 which is slidably mounted in the bore 17 is provided with heads 27 and 28 and the plunger is retained in the opening by a screw 29, the inner end of which is positioned between the heads of the plunger. The plunger is actuated by a cam 30 on the lever 18 after a pin 31 extended through a flange 32 is pressed inwardly with the reamer 12 to the position shown 35 in Fig. 5 wherein the reamer extends through a bushing 33 in one side of the flange and into a hammer butt or jack, as indicated by the numeral 34.

With the parts arranged in this position the 40 hand lever 15 is released and the reamer is rotated by the thumb and forefinger of the operator with the thumb and forefinger gripping the knurled surface of the head 14. The spinning movement of the reamer removes corrosion, grease or the like in the bushing 33. After reaming the bushing 33 in one side the hand lever 18 is drawn upwardly whereby the plunger 16 drives the pin 31 back to its position in the flange. The 45 flange may be turned over whereby the same operation is performed on the opposite side with the reamer forcing the pin from the bushing and reaming the opening and with the plunger returning the pin to the position particularly as shown in Fig. 3.

By this means all guess work is eliminated and the connection of the flange to the hammer butt or jack is restored to its original condition.

The flange 32 is retained in position with a guide 35, as illustrated in Fig. 4, the guide being pivotally mounted on the under surface of the upper handle 10 with a pin 36 and being held in position with a stud having a head 37, the stud extending through a slot 38 in the guide. The extended end of the guide 35 is provided with a slot 39 in which the flange 32 is positioned whereby the opening in the bushing of the flange is aligned with the reamer 12.

Figure 6 illustrates the positions of the parts with the pin returned by the plunger after reaming the bushing in the upper side of the flange and Fig. 7 is a view similar to that shown in Fig. 6 showing the position of the flange reversed whereby the reamer is in position for reaming the bushing on the opposite side of the flange.

In Fig. 8 the hammer butt 34 and flange 32 with the pin 31 are assembled and the parts are retained in position in which they are aligned with the reamer by the guide 35.

In Figs. 9, 10, and 11 the shank of the reamer is replaced with a pin holder 40 having a socket 41 therein in which a pin, as indicated by the numeral 42 and as illustrated in Fig. 14 is positioned and after reaming the bushing of the flange, such as the flange 32 a pin may be inserted in the socket 41 and with the holder 40 in the opening 26 of the upper handle the new pin may drive the old pin through the flange and hammer butt or jack. With the new pin in position the pin holder is reversed, as shown in Fig. 11 whereby the pin is forced through both sides of the flange with the old pin, as indicated by the numeral 43, which shows the pin dropping out. In this operation the plunger 16 is omitted so that the old pin 43 is free to drop through the opening 17 in the lower handle. The pin holder may also be provided with a knurled head as indicated by the numeral 44 and the head 44 is retained in position with a set screw 45.

With the parts arranged in this manner the reamer 12 with the head 14 thereon is positioned in the opening 26 of the upper handle and a piano action flange with a hammer butt or jack therein, as illustrated in Fig. 8, is positioned between the handles with the pin of the piano action aligned by the guide 35 with the reamer and with the parts in position the reamer is forced inwardly with the hand lever 15 whereby the reamer passes through the upper side of the flange and into a tongue of the hammer butt or jack with the pin extended from the lower side of the flange. With the parts in this position the operator spins the reamer, reaming out the bushing in the upper side of the flange and upon completion of this operation the hand lever 18 is drawn upwardly whereby the plunger drives the pin back into the opening in the bushing. The position of the flange with the hammer butt or jack therein is reversed and the action repeated for the opposite side.

By this means the pivotal connection between the flange and hammer butt or jack is accurately refinished without over enlarging the openings of the bushings, however, should it be desired to replace the pin the pins may be removed and replaced with the parts as illustrated in Figs. 9, 10 and 11.

It will be understood that modifications, within the scope of the appended claims, may be made in the design and arrangement of the parts without departing from the spirit of the invention.

What is claimed is:

1. A piano action repair tool comprising a pair of handles pivotally connected at one of the ends thereof, a hand lever pivotally mounted on each of said handles, each of said handles having an opening therethrough and the opening of one handle being aligned with the opening of the other handle, and a reamer slidably mounted in the opening of one handle and positioned to be actuated by the hand lever pivotally mounted on said handle, a plunger slidably mounted in the opening of the other handle and positioned to be actuated by the hand lever pivotally mounted on said other handle to press a pin of a piano action flange positioned between said handles into said flange.

2. A piano action repair tool comprising a pair of handles pivotally connected at one of the ends thereof, a hand lever pivotally mounted on

each of said handles, each of said handles having an opening therethrough and said openings positioned perpendicular to a plane extended between the handles, the opening of one of the handles being aligned with the opening of the other handle, a reamer having a knurled head on an extended end thereof slidably mounted in the opening of one handle and positioned to be actuated by the hand lever pivotally mounted on said handle, a piano action hinge guide positioned on one of said handles and a plunger slidably mounted in the opening of the handle opposite to the handle in which the reamer is positioned and said plunger positioned to be actuated by the hand lever pivotally mounted on said handle.

3. A piano action repair tool comprising a pair of handles pivotally connected at one of the ends thereof, a hand lever pivotally mounted on each of said handles, each of said handles having an opening therethrough and said openings positioned perpendicular to a plane extended between the handles, the opening of one of the handles being aligned with the opening of the other handle, a reamer having a knurled head on an extended end thereof slidably mounted in the opening of one handle and positioned to be actuated by the hand lever pivotally mounted on said handle, a piano action hinge guide positioned on one of said handles, a plunger having a head on each end and with the intermediate portion relieved slidably mounted in the opening of the handle opposite to the handle in which the reamer is positioned and said plunger positioned to be actuated by the hand lever pivotally mounted on said handle, and a set screw threaded in the handle and extended into the opening of the handle and relieved portion of the plunger for retaining the plunger in the handle, the knurled head facilitating spinning the reamer with the thumb and forefinger of a hand.

4. A piano action repair tool comprising a pair of handles pivotally connected at one of the ends thereof, a hand lever pivotally mounted on each of said handles, each of said handles having an opening therethrough and said openings positioned perpendicular to a plane extended between the handles, the opening of one of the handles being aligned with the opening of the other handle, a reamer having a knurled head on an extended end thereof slidably mounted in the opening of one handle and positioned to be actuated by the hand lever pivotally mounted on said handle, said reamer having an enlarged shank positioned in the bore of the handle and said knurled head being secured to the shank with a set screw, a piano action hinge guide positioned on one of said handles and a plunger slidably mounted in the opening of the handle opposite to the handle in which the reamer is positioned and said plunger positioned to be actuated by the hand lever pivotally mounted on said handle, said guide being pivotally mounted on the handle.

5. In a piano action repair tool, the combination which comprises an upper handle having an enlarged section adjacent one end with a gripping section extended from said enlarged section,

a lower handle having an enlarged section adjacent one end and having a gripping section extended from the enlarged section, means pivotally connecting the ends of the handles adjacent which said enlarged sections thereof are positioned, said enlarged sections of each handle having a bore positioned perpendicular to a plane extended from the pivotal connection midway between the handles and the bore of the enlarged section of one handle being aligned with the bore of the enlarged section of the other handle, a reamer having a knurled head slidably mounted in the bore of the upper handle, a hand lever having a cam thereon pivotally mounted on the enlarged section of the upper handle and positioned whereby the cam engages the head of the reamer upon moving the extended end of the lever toward the handle on the enlarged section of which it is mounted, a plunger having enlarged ends slidably mounted in the opening of the lower handle, and a hand lever also having a cam thereon pivotally mounted on the enlarged section of the lower handle and positioned whereby the cam engages the plunger upon movement of the hand lever toward the handle upon which it is pivotally mounted.

6. In a piano action repair tool, the combination which comprises an upper handle having an enlarged section adjacent one end with a gripping section extended from said enlarged section, a lower handle having an enlarged section adjacent one end and having a gripping section extended from the enlarged section, means pivotally connecting the ends of the handles adjacent which said enlarged sections thereof are positioned, bores positioned perpendicular to a plane extended from the pivotal connection midway between the handles through said enlarged sections of the handles and the bore of the enlarged section of one handle being aligned with the bore of the enlarged section of the other handle, a reamer having a knurled head slidably mounted in the bore of the upper handle, a hand lever having a cam thereon pivotally mounted on the enlarged section of the upper handle and positioned whereby the cam engages the head of the reamer upon moving the extended end of the lever toward the handle on the enlarged section of which it is mounted, a plunger having enlarged ends slidably mounted in the opening of the lower handle, a hand lever also having a cam thereon pivotally mounted on the enlarged section of the lower handle and positioned whereby the cam engages the plunger upon movement of the hand lever toward the handle upon which it is pivotally mounted, and a guide pivotally mounted on the upper handle and having a notch therein positioned to receive a piano action flange with a pin extended through the flange aligned with a reamer in the bore of said upper handle.

CHARLES B. ARCHER.
